United States Patent

Des. 241,225
Patented Aug. 31, 1976

241,225

BOTTLE

Ronald Harold McCurdy, Willowdale, Ontario, Canada,
assignor to Wampole Limited, Don Mills, Ontario,
Canada

Filed Feb. 11, 1975, Ser. No. 549,091

Term of patent 14 years

Int. Cl. D9—01

U.S. Cl. D9—47

FIG. 1

FIG. 2

FIG. 1 is an elevational view of a bottle showing my new design; and

FIG. 2 is an elevational view thereof looking from the left of FIG. 1.

The vertical lines on the closure illustrate vertical striations and the top of the closure is plain and unornamented.

I claim:

The ornamental design for a bottle, as shown and described.
